[57] CLAIM

The ornamental design for a cover for a transport cargo heater unit, as shown and described.

DESCRIPTION

FIG. 1 is a perspective view of a cover for a transport cargo heater unit showing our new design;

FIG. 2 is a front elevational view thereof, on a reduced scale;

FIG. 3 is a top plan view thereof, on a reduced scale, the bottom being a mirror image of that shown;

FIG. 4 is a left side elevational view thereof, on a reduced scale; and

FIG. 5 is a right side elevational view thereof, on a reduced scale.

The broken lines shown in FIG. 1 are for illustrative purposes only and form no part of the claimed design.

FIG. 1

FIG. 3

FIG. 2

FIG. 4

FIG. 5
